Specification for Design.

Patented Jan. 7, 1913.

Application filed June 3, 1912. Serial No. 701,449. Term of patent 14 years.

To all whom it may concern:

Be it known that I, DAVID C. WHEELER, a citizen of the United States, residing at Bridgeport, county of Fairfield, State of Connecticut, have invented a new, original, and ornamental Design for Shear-Blades, of which the following is a specification, reference being had to the accompanying drawing, forming part thereof.

In the accompanying drawing the figure is a face view of a shear blade embodying my new design.

I claim:—

The ornamental design for a shear blade as shown.

In testimony whereof I affix my signature in presence of two witnesses.

DAVID C. WHEELER.
